UNITED STATES PATENT OFFICE.

SIDNEY L. MODÉE, OF CHICAGO, ILLINOIS, ASSIGNOR TO EDWARD W. EVERETT, OF CHICAGO, ILLINOIS.

DEVICE FOR TIGHTENING WIRES OR RODS.

Application filed February 26, 1912, Serial No. 679,806. Renewed March 17, 1922. Serial No. 544,637.

To all whom it may concern:

Be it known that I, SIDNEY L. MODÉE, a citizen of the United States, residing at Chicago, in the county of Cook and State of Illinois, have invented a certain new and useful Improvement in Devices for Tightening Wires or Rods, of which the following is a specification.

This invention relates to improvements in devices for tightening wires or rods, and is particularly adapted for tightening the wires or rods used in forming the frame work of concrete buildings wherein said wires or rods are to be embedded in the concrete. In one method of forming these concrete buildings, for example, a continuous wire is looped back and forth around supporting pipes or beams. In this construction the entire length of wire must be stretched or tightened so as to permit the wires and tubes or beams to be properly embedded in the cement without undue sagging. These wires of necessity are of large diameter and require great force to properly stretch them. This has been found in practice to be a difficult task and one of the objects of the present invention is to provide means for easily and effectively tightening these wires.

Referring now to the accompanying drawings, I have shown one form of device embodying the invention.

Figure 1 is a side elevation of one form of the device:

Figure 2 is a sectional view taken on line 2-2 of Figure 1;

Figure 3 is a sectional view through a portion of the frame of the building, showing one of the tightening devices in position;

Figure 4 is a view taken at right angles to Fig. 3, showing a portion of the frame of the building, with the continuous wire looped back and forth thereon, and two co-operating devices in position.

Like numerals refer to like parts throughout the several figures.

In the construction illustrated, there is provided a bar 1, provided with teeth 2 and having at one end a hook 3, by means of which the bar is fastened to a stationary part, such as a pipe or beam. Mounted upon the bar 1 so that it may slide therealong is a gripping block 4. As illustrated, this gripping block or portions thereof, entirely surround the bar (see Figure 2). The

gripping block 4 is provided at one side with a wire supporting projection 5. A gripping cam 6 is movably mounted on the pin 7 located above the projection 5. This cam has a roughened surface so that it will grip the wire and is provided with a controlling handle 8. When the handle 8 is moved forward, a large part of the cam is brought into contact with the wire so as to tightly grip it between the cam and the projection 5, the tension on the wire increasing the gripping action. An actuating handle 9 is pivotally connected to the other side of the gripping block, as, for example, by being mounted upon the pin 10. A pivoted dog 11 is pivotally connected to the actuating handle 9 by means of pin 12, and is provided with an engaging end 13 which engages the teeth 2 on the bar 1. Pivotally connected with the gripping block is a dog 14 which is provided with an end 15 which engages the teeth 2 on the bar 1. The dog 14 is connected to the bar 1 by pin 16. It will be noted that the dogs 11 and 14 engage the bar 1 on opposite sides of the actuating handle 9.

Referring now to Figures 3 and 4, I have shown the frame work of a concrete building consisting of pipes 17 and 18 separated a suitable distance, and having a continuous wire 19 looped back and forth about the pipes so as to make a proper re-inforced wall, floor or ceiling. In placing this wire in position, one end is fastened to a fixed part and it is then looped back and forth about the pipes and drawn taut. In using the device shown in Figures 1 and 2 for stretching the wires, I prefer to use two of these devices which may be placed side by side as shown in Figure 4, or may be separated at any suitable distance, one being clamped to one portion of the wire and the other being clamped to another portion, the hooks 3 in each case being hooked around the pipe 17. A cross piece 20 is preferably connected to one end of the bar 1, said cross piece engaging two or more wires when the device is in position so as to keep such device in an upright position in order that it may be easily and efficiently operated. As herein shown, this cross piece passes through an opening in the end of the bar 1.

The use and operation of my invention are as follows:

When the device is to be used in tight-

ening a continuous wire used in the frame work of a concrete building, for example, the wire is first laced back and forth between the tubes 17 and 18. The hook 3 of 5 the bar 1 is then hooked over one of these pipes as for example, pipe 17, and the wire clamped between the cam 6 and the projection 5, the supporting piece 20 resting on top of the wires so as to hold the device in 10 an upright position. Before clamping the wire, the gripping block 4 is moved up near the front end of the bar 1. After the wire is clamped, one or more operators grasp the actuating handle 9 and move the upper 15 end thereof in a direction away from the hook 3. The end 13 of the dog 11 engages one of the teeth 2 so as to prevent the movement of the dog and to force the gripping block 4 along the bar 1. The dog 14 is 20 carried with the gripping block and slides on the beveled face of one of the teeth 2 and then drops over said tooth so as to engage it, as shown in Figure 1. The handle 9 is then moved in the opposite direction. 25 The dog 11 now slides up on the beveled face of one of the teeth 2 and drops over said tooth into the next space, dog 14 in the meantime preventing the backward movement of the gripping block 4, and 30 hence, of the wire to which it is connected. The handle is now again moved in a direction away from the hook 3 and the gripping block 4 moved up a distance equal to the space between the teeth. This movement 35 is repeated until the wire is brought to the proper tension, or until the dog 14 reaches the last tooth on the bar. A second device see Fig. 4 is now connected with the wire near the point where the first device is 40 connected preferably with an adjacent loop and is then operated so as to tighten the wire. After the wire has been sufficiently tightened, the first device is released from the wire and connected with it again on the 45 other side of the second device and the operation repeated. It will be noted that one of the devices holds the wire and prevents it from becoming loosened again while

the other is being removed and again connected with the wire. The handle 9 is 50 made long so as to multiply the power and it will be seen that by means of these devices, the wire can be easily and quickly brought to any desired tension and may be held under such tension, and that this result can be secured regardless of the length 55 of the wire or the number of times it is looped about the end supports or pipes.

It will be seen, as illustrated in Fig. 4, 60 that there is a continuous wire looped back and forth around fixed supports, and a plurality of wire gripping devices adapted to be attached to different loops of the wire, a bar with which each wire gripping device is connected, and a hook connected with 65 each bar by means of which it may be fastened to the fixed support, in the present case, the tube 17, the gripping devices being successively moved along the bars to 70 tighten the wire.

I claim:

A wire-tightening device comprising a bar having teeth on one side thereof, means for holding said bar against longitudinal movement while the device is being used, a gripping block slidably connected with said bar and provided with means for gripping the wire, said gripping device located at one side of said bar so that the bar and the wire gripping by the gripping device are side by side, a handle pivotally connected with said gripping block, a dog pivoted to said handle and adapted to engage the teeth on the bar and a second dog pivoted to said gripping block and adapted to engage the teeth on the bar, and a cross piece connected with said bar and adapted to extend across a plurality of wires so as to support the device in an upright position.

Signed at Chicago, Illinois, this 24th day 90 of February, 1912.

SIDNEY L. MODÉE.
